CLAIM

The ornamental design for a human body detector, as shown and described.

DESCRIPTION

FIG. 1 is a front elevational view of a human body detector showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front left perspective view thereof;

FIG. 7 is a rear left perspective view thereof;

FIG. 8 is a front right perspective view thereof;

FIG. 9 is a rear right perspective view thereof;

FIG. 10 is a rear right perspective view thereof with a sensor dome at a first rotated position on a base;

FIG. 11 is a rear left perspective view thereof with the sensor dome at a second rotated position; and,

FIG. 12 is a rear right perspective view thereof with the sensor dome at a third rotated position.
